METHOD AND MEANS FOR ELIMINATING CAPACITIVE COUPLING

Application filed February 27, 1925. Serial No. 11,973.

This invention is directed to the neutralization of capacitive coupling between electric circuits, especially where such coupling is unavoidable and causes undesirable reactions between the circuits.

The invention is particularly applicable to audion circuits. The term "audion" as used herein is defined as any electric device comprising a cathode, herein referred to as the "filament"; an anode, referred to as the "plate"; and an electrostatic control electrode, referred to as the "grid". The arrangement of the electrodes is such that variations in the potential of the grid relative to the filament affect the current between plate and filament in a manner equivalent to the proportional changes in the potential of the plate relative to the filament. Because of the finite dimensions of the audion, the capacity between any two of the electrodes is sufficient to be appreciable and is, in addition, usually increased by capacity between the external connections to said two electrodes. In a common case where one resonant circuit is associated with the grid and another resonant circuit is associated with the plate, this inherent capacity existing between grid and plate causes capacitive coupling between those two circuits, which coupling may in turn cause undesirable reactions, such as so-called regenerative action or the generation of electrical oscillations which interfere with the operation of the system as a whole.

Capacitive coupling can, by means of this invention, be neutralized and regenerative action eliminated, whereby regenerative oscillation becomes impossible. The present invention is equally applicable to a great variety of circuits, employing high or low power, as, for example, carrier-wave telephony, power amplifiers in radio transmitting circuits, or radio receiving sets. Although several other methods have been suggested for this purpose, only a few of those methods satisfy the requirement that adjustments necessary for neutralizing the capacitive coupling be independent of the frequencies of alternating currents to which the system as a whole must be accommodated. The few other methods which do meet this requirement embody cir-

cuit arrangements essentially different from and more complex than those herein described, as will be clearly demonstrated hereinafter. This application is a continuation in part of application Serial No. 739,080, filed September 22, 1924.

It is the purpose of the present invention to neutralize capacitive coupling existing effectively between any two or more circuits by means of a rearrangement including the introduction of capacities, either inherent such as introduced by the juxtaposition of the wiring or other component apparatus, such as audion electrodes, or in the form of added condensers where necessary, to form a network of pure capacities which can be adjusted so that there is no resultant capacitive coupling between any two of said circuits. The principles and circuit arrangements utilized in the practice of this invention are herein-after described in detail with the aid of illustrations of a preferred embodiment.

Fig. 1 is an elementary diagram of a pure capacity bridge illustrating the basic principle employed in this invention;

Fig. 2 is a circuit diagram showing one method of applying this invention to an audion circuit;

Fig. 3 illustrates an alternative method of applying this invention to an audion circuit;

Fig. 4 is a circuit diagram of a radio receiver employing a two-stage radio-frequency amplifier which utilizes the principles illustrated in Fig. 3.

In Figs. 1 to 3, inclusive, reference characters A and B represent electric circuits of any nature whatsoever; i. e., tuned, untuned or resonant circuits. Likewise, reference characters C₁, C₂, C' and C'' represent capacities forming the four arms of a pure capacity bridge, and may be of any nature whatsoever, as, for example, condensers, or natural inherent capacities between circuit elements, or between audion electrodes. When one of these capacities is by preference solely a natural inherent capacity, it is shown connected in dotted lines such as C' in Figs. 2 and 3. While the capacities represented in the figures as being connected by dotted lines represent natural or inherent capacities, it is to be

understood that others of the bridge capacities may also be natural or inherent capacities. As long as equation (1), given below, is satisfied, the balance will obtain regardless of whether the capacities be inherent, or 5 added in the form of condensers, or both combined. In the last case, it is the effective value of the combined capacities which is to be considered in attaining a balance. For 10 example, capacity C_1 of Fig. 2 is to be taken as including the inherent grid-filament capacity of the audion 1; and referring to Fig. 3, the bridge capacity C_1 , which is connected between the plate and the filament of the 15 audion 3, must be taken as including the effective capacity existing between the plate and filament electrodes, and would thus comprise the inherent plate-filament capacity of the audion and the distributed capacity of the 20 coil 4 and battery 12 added to the additional capacity or condenser symbolically represented at C_1 .

The elementary diagram shown in Fig. 1 represents a pure capacity bridge comprising 25 four capacities, C' , C'' , C_1 and C_2 connected with two circuits A and B, these circuits comprising, respectively, the conjugate arms of the bridge. Reference to the figure will show that the circuit A is connected to one pair of 30 conjugate points of the bridge and that the circuit B is connected to the other pair of conjugate points. The values of the capacities are adjusted as necessary until no part of the voltage generated between the terminals of one circuit is impressed between the terminals of the other circuit. There must 35 be no inductive coupling or resistance coupling between the two circuits if an accurate balance is to be obtained. The quantitative 40 condition for an accurate balance or a neutralization of capacitive coupling between circuits A and B is:

$$\frac{C'}{C''} = \frac{C_1}{C_2} \quad (1)$$

In the fundamental circuit shown in Fig. 1, 45 as well as those shown in the other figures, and for the purposes of this description, it is assumed that these four fundamental capacities are adjusted to satisfy the condition represented in the above equation, and that each of the four capacities is intended to represent the total capacity effectively connected between the points indicated, where, as above 50 described, such capacity comprises solely an inherent capacity or solely an added capacity, or both inherent and added capacities together. Inductive coupling, or resistance coupling, may then be introduced between the 55 circuits if required, but the capacitive coupling will remain neutralized as long as equation (1) is satisfied.

Fig. 2 shows the principle of this invention applied to a simple audion circuit. Here, as 60 in Fig. 3, reference characters A and B can

be regarded as the input and output circuits, respectively, of an amplifier stage containing an audion 1, which includes plate P, grid G and filament F. For simplicity, the filament (F) is shown in this and the other figures to be of the simple hot-cathode type. It 70 should be understood, however, that the present invention is equally applicable to an audion having an indirectly heated cathode, in which event the word "filament" as used in the present specification and appended claims is, of course, intended to refer to such cathode. Since, according to common practice, the input circuit of an audion is always connected to the grid and the output circuit to the plate, the natural capacity between the grid and plate ordinarily causes capacitive coupling between the audion input and output circuits. By arranging the capacity bridge as shown, (which for convenience 75 may be termed an "input-circuit bridge") this capacitive coupling is balanced and neutralized, because the input and output circuits are, respectively, the conjugate arms of a balanced bridge. In this, as well as in the 80 circuit arrangements illustrated in the other figures the capacity C' may be considered as causing undesirable coupling to be neutralized. The grid leak or high resistance 85 90 connected between the grid and the filament circuit is introduced for the usual purpose of maintaining a constant average grid potential with respect to the filament. Such a resistance is a simple means for effecting the required grid potential, which may be either 95 positive or negative with respect to the filament, as required by the particular audion employed, and may be obtained in many other ways, such as by the use of an impedance, or by a separate battery. Maximum amplification 100 will be obtained when as high an input voltage as possible is impressed upon the grid of the audion, and it is therefore preferable in the arrangement of Fig. 2, that the ratio 105 of capacities $\frac{C_2}{C_1}$ be considerably greater than 110 unity.

The circuit arrangement illustrated in Fig. 3 is in general similar to that shown in Fig. 2 except that the neutralizing bridge is inverted with respect to the grid and plate, and 115 may be termed an "output-circuit bridge". It may here be pointed out that the "output-circuit bridge" for balancing and neutralizing undesired coupling between the input and output circuits—especially the plate-grid capacity coupling—of the common three-electrode audion, will always include the natural inherent plate-filament capacity of the audion and will not include the grid-filament capacity thereof; while the "input-circuit bridge" above described in connection with 120 Fig. 2 will include the natural inherent grid-filament capacity of the audion and will not include the plate-filament capacity thereof. 125 130

In this figure reference character A represents the input circuit connected to grid G and filament F of audion 3. Capacity C' represents the natural inherent capacity existing between the grid G and plate P. Output circuit B is associated with the capacities C₁, C₂ and C'', which capacities are adjusted so that the balanced condition expressed by equation (1) between conjugate circuits A and B is obtained. A choke coil 4 of high inductance and low electrostatic capacity is inserted in the plate circuit between plate P and plate battery 12 in order to by-pass the direct plate current past the capacities of the bridge, but which at the same time offers a high impedance to radio frequency currents flowing in the plate-output circuit, thus keeping those currents from flowing through the "B" battery 12. For convenience, the circuit P, 4, 12, F may be called the "plate circuit" to distinguish from the alternating current output circuit "B".

Fig. 4 shows a circuit diagram of a radio receiver employing two stages of tuned radio-frequency amplification and a detector, or rectifier. This circuit arrangement utilizes the principle described above with reference to Fig. 3 and includes an output-circuit bridge, or capacity network in the plate-output circuit of each of the radio-frequency amplifying audions 16 and 17, respectively, of which the input circuit and output circuit of each audion form conjugate arms of a balanced bridge as previously described. The input circuit of the first audion 16 comprises an antenna 25 and ground 29, a series condenser 28 and an auto-transformer T, of which the primary-to-secondary ratio may be about 1:2.8. This transformer is tuned by variable condenser 30 connected across its extremities. The output circuit of this audion includes an inductance 19 tuned by a variable condenser 20, and is coupled to the input circuit of the next succeeding audion 17 through a capacity 21. The second stage of amplification is similar to the first and is coupled to the input of the detector or rectifier audion 18 by capacity 22. In the plate circuit of each radio-frequency amplifier between the plate electrode and plate battery 12 is a choke coil 4, preferably of high inductance and low electrostatic capacity, provided to by-pass the direct current directly from the filament circuit to the plate. If the inductance of this coil is about 10 millihenries, it will not short circuit the radio-frequency current. It should here be noted that each radio-frequency amplifying stage includes a capacity bridge C₁, C₂, C' and C'' similar to that described above in connection with Fig. 3, where the reference characters correspond. As described in connection with Fig. 2 above, a grid leak or high resistance 2 may be connected between the grid and the filament circuit for

the usual purpose of maintaining a constant average grid potential with respect to the filament. High-frequency by-pass condensers 23, 24 and 26 are provided to introduce a low resistance path to high-frequency currents across the filament battery 11, plate battery 12 and telephones 27, respectively. Maximum amplification in this arrangement will also be obtained when as high an input voltage as possible is impressed upon the grid of the audion, but contrary to Fig. 2, it is here preferable that the ratio of capacities C₁ be small. 70 76

As is well known, the output impedance of an audion is ordinarily much less than the input impedance thereof; furthermore, the maximum transfer of energy will be attained when the impedances, which are connected respectively in the output and input circuits 80 85 of the audions, are chosen so as to be of values as nearly as possible the same as the respective output and input impedance values of the audions. Accordingly, the capacity value of condenser C₁ connected from plate to filament would usually be much larger than the capacity value of condenser C₂ connected between the grid and filament of the next audion, but which would also usually be connected in series with a coupling device, such 90 95 as condenser 21 or 22.

The capacity bridge represented in Fig. 4 as C₁, C₂, C' and C'', wherein C' represents the undesirable grid-plate capacity to be neutralized, may, for example comprise capacities of the following values: 100

C₁=300 micro-microfarads;
C₂=50 micro-microfarads;
C'=3 micro-microfarads;
C''=1/2 micro-microfarad; 105
C' being an accidental inherent capacity of 3 micro-microfarads. The other values of capacity mentioned, were found, when associated with C' according to the present invention, to eliminate completely all tendency toward regeneration or feed-back due to that inherent capacity. Of course, values of capacity other than those just given might be used provided that the quantitative relation expressed in equation (1) be realized, and preferably that the ratios of capacities before mentioned be maintained. 110 115

It should be noted that in the case shown in Figs. 2, 3 and 4 it is a distinct advantage to make the ratio $\frac{C'}{C_1}$ as small as possible without materially affecting the associated input and output circuits. For instance, in the amplifier described in connection with Fig. 4 this ratio is approximately 1/100, which in that case is entirely satisfactory, although in other cases this ratio might well be somewhat larger. 120 125

Such a ratio is desirable in order that a maximum degree of amplifying action may 130

be attained. With a given difference of potential between the grid and filament impressed upon capacities C' and C_1 in series, the grid would be at the same potential as the plate if C' were infinitely large; hence, it is desirable that C' be as small as possible in order that there may be a large potential drop from the plate to the grid across C' , as compared with the potential drop across C_1 . Conversely, as the capacity value of C_1 is increased, the potential on the plate with respect to the filament is decreased due to current flowing through C_1 . Hence, it is preferable that C_1 be as small as possible, and that C_1 be large as compared with C' within the limits determined by the tuning ranges desired, by the voltage characteristic of the audion, by the output and input impedances of the audions employed, and by the practicable values of capacities C'' and C_2 . The reason for the desirability of this ratio of capacity values may also be described in another way, (see also Fig. 3), namely: that an input voltage impressed across the grid and filament, or input circuit (A), does not introduce a voltage in the output circuit (B) because those two circuits are conjugate arms of a balanced bridge, but this input voltage does introduce a voltage between the plate and filament across one arm, C_1 , of the bridge. This effect is equivalent to introducing a conductance across the grid circuit from grid to filament which increases with the ratio $\frac{C'}{C_1}$, making the grid circuit less efficient and consequently decreasing the degree of amplification. Hence, the ratio $\frac{C'}{C_1}$ should be as small as possible.

For the reasons above pointed out, the value of the capacity C_1 added between the plate and filament should be large compared with the natural inherent plate-grid capacity, C' . Hence, since the magnitude of the inherent plate-filament capacity is normally comparable to the magnitude of the grid-plate capacity, the value of the total capacity at C_1 between the plate and filament electrodes will likewise be substantially larger than that of the natural inherent plate-filament capacity.

I claim:

1. An amplifier including an audion having an input circuit and an output circuit, one terminal of said output circuit being connected to the plate electrode of said audion and through a capacity to the filament circuit of said audion, the second terminal of said output circuit being connected through a second capacity to the grid electrode of said audion and through a third capacity to said filament circuit, whereby undesirable capacitive coupling between said grid and plate electrodes is neutralized.
2. An amplifier including an audion and a

condenser-tuned inductance, said audion having undesirable capacitive coupling between the grid and plate electrodes thereof, and means for neutralizing said capacitive coupling comprising a capacity effectively connected between the plate electrode and the filament, and a second and third capacity effectively connected in series between the grid electrode and the filament, said inductance being connected from the plate electrode to a point between said second and said third-mentioned capacities. 70

3. In an amplifier, an audion having undesirable capacitive coupling between the plate and grid electrodes thereof, an inherent capacity between the plate and the filament, an output circuit for said audion including a coil, and means for neutralizing said undesirable coupling comprising a capacity between the plate and the filament, said capacity being at least in part said inherent capacity, and two condensers connected in series between the grid and the filament, said coil being connected from the plate to a point between said two condensers. 80

4. A radio-frequency amplifier comprising two audions, each audion including grid, plate and filament electrodes, the filament electrodes of said audions being connected together, a coupling system interposed between said audions, said coupling system including a single radio-frequency coil associated with a blocking condenser and being connected between the plate electrode of one audion and the grid electrode of the other audion and including four capacities effectively connected two from the terminals of said coil to the filaments and two from the terminals of said coil to the remaining electrode of one of said audions. 90

5. A radio-frequency amplifier comprising two audions whose filaments are connected together through a filament system, each audion including grid and plate electrodes, a coupling system interposed between said audions, said coupling system including a single radio-frequency coil associated with a blocking condenser and being connected between the plate electrode of one audion and the grid electrode of the other audion and including four capacities effectively connected two from the terminals of said coil to the grid electrode of the first audion and two from the terminals of said coil to the filament system. 100

6. A radio-frequency amplifier comprising two audions whose filaments are connected together through a filament system, each audion including grid and plate electrodes, a coupling system interposed between said audions, said coupling system including a single radio-frequency coil associated with a blocking condenser and being connected between the plate electrode of one audion and the grid electrode of the other audion and including four capacities effectively connected two from the terminals of said coil to the grid electrode of the first audion and two from the terminals of said coil to the filament system. 110

115

nals of said coil to the grid electrode of the first audion and two from the terminals of said coil to the filament system, and a fifth capacity connected in parallel with said coil for tuning the same to radio frequencies.

5 7. A radio-frequency amplifier comprising two audions whose filaments are connected together through a filament system, each audion including grid and plate electrodes between which exists an inherent coupling capacity, an interposed coupling system including a single radio-frequency coil associated with a blocking condenser and connected between the plate electrode of one audion and the grid electrode of the other audion and including 10 four capacities, one of which comprises said grid-plate capacity, effectively connected two from the terminals of said coil to the grid electrode of the first audion and two from the 15 terminals of said coil to the filament system, said four capacities together comprising a balanced bridge by means of which undesirable reactions due to the coupling introduced by said grid-plate capacity are substantially 20 eliminated.

25 8. A radio-frequency amplifier comprising two audions, each audion including grid, plate and filament electrodes, the filament electrodes of said audions being connected together, inherent coupling capacity between said grid and plate electrodes, a coupling system interposed between said audions, said coupling system including a single radio-frequency coil associated with a blocking condenser and connected between the plate electrode of one audion and the grid electrode of the other audion and including four capacities, one of which includes said grid-plate capacity, effectively connected two from the 30 terminals of said coil to the filaments and two from the terminals of said coil to the remaining electrode of one of said audions, said four capacities together comprising a balanced bridge by means of which undesirable reactions due to the coupling introduced by said grid-plate capacity are substantially 35 eliminated.

40 9. A radio-frequency amplifier comprising two audions, each audion including grid, plate and filament electrodes, the filament electrodes of said audions being connected together, a coupling system interposed between said audions, said coupling system including a single radio-frequency coil associated with a 45 blocking condenser and being connected between the plate electrode of one audion and the grid electrode of the other audion, and including four capacities effectively connected two from the terminals of said coil to the 50 filaments and two from the terminals of said coil to the remaining electrode of one audion, and a fifth capacity connected in parallel with said coil for tuning the same to radio 55 frequencies.

60 10. A radio-frequency amplifier comprising

ing two audions, each audion including grid, plate and filament electrodes, the filament electrodes of said audions being connected together, inherent coupling capacity between said grid and plate electrodes, a coupling system interposed between said audions, said coupling system including a single radio-frequency coil associated with a blocking condenser and connected between the plate electrode of one audion and the grid electrode of the other audion and including four capacities, one of which includes said grid-plate capacity, effectively connected two from the terminals of said coil to the filaments and two from the terminals of said coil to the remaining electrode of one of said audions, said four capacities together comprising a balanced bridge by means of which undesirable reactions due to the coupling introduced by said grid-plate capacity are substantially eliminated, and a fifth capacity connected in parallel with said coil for tuning the same to radio frequencies.

65 11. A radio-frequency amplifier comprising two audions whose filaments are connected together through a filament system, each audion including grid and plate electrodes between which exists inherent coupling capacity, an interposed coupling system including a single radio-frequency coil associated with a blocking condenser and connected between the plate electrode of one audion and the grid electrode of the other audion and including four capacities, one of which comprises said grid-plate capacity, effectively connected two from the terminals of said coil to the grid electrode of the first audion, and two from the terminals of said coil to the filament system, said four capacities together comprising a balanced bridge by 70 means of which undesirable reactions due to the coupling introduced by said grid-plate capacity are substantially eliminated, and a fifth capacity connected in parallel with said coil for tuning the same to radio-frequencies.

75 12. In an audion amplifier having an input circuit and an output circuit connected to elements of an audion, and a natural capacity inherent between two of said elements whereby undesired reactions are produced, the method of reducing substantially to zero said 80 undesired reactions which consists in introducing in said output circuit a plurality of capacitive reactions without introducing inductive reactions, one of said capacitive reactions being due to an inter-element capacity, dividing said capacitive reactions into two portions and balancing one of said portions against the other of said portions.

85 13. In an amplifier including an audion having grid, plate and filament electrodes, an input circuit connected to said grid, an output circuit connected to said plate, and natural inherent capacity effectively connected between said grid and plate electrodes,

whereby undesired reactions are produced, the method of reducing substantially to zero said undesired reactions which consists in introducing in said output circuit a plurality of capacitive reactions without introducing inductive reactions, one of said capacitive reactions being at least in part due to a natural inherent capacity effectively existing between said plate and said filament, dividing 10 said capacitive reactions into two portions and balancing one of said portions against the other of said portions.

14. The combination with an audion having grid, plate and filament electrodes of a circuit connected to the plate and containing 15 two condensers, a connection from the filament to a point between the said condensers, a circuit connected to the grid, and a capacity inserted between the two circuits to balance 20 the capacity between the grid and plate of the audion.

15. The combination with an audion having grid, plate and filament electrodes and having an input circuit and an output circuit, of a capacity in the output circuit divided into two parts and having a lead connected from its midpoint to the filament and an end connected to the plate electrode, and a balancing capacity connected between the 30 grid electrode and the other end of the divided capacity.

16. An audion amplifier stage having an input circuit, an output circuit, an audion capacitively coupling said circuits, said input circuit being connected between the grid and filament electrodes of said audion, and a balanced network of pure capacities only, including the coupling capacity, and having as conjugate arms said input and output circuits.

17. An electric system including an input circuit, an output circuit, an audion capacitively coupling said circuits, and a balanced network of pure capacities only, including the coupling capacity as one arm of said network and a capacity between the plate and filament electrodes of said audion as another arm of said network, said input and output circuits being connected respectively as conjugate arms of said network.

18. An electric system including an input circuit, an output circuit, an audion capacitively coupling said circuits, a balanced network of pure capacities only, including the coupling capacity as one arm of said network and a capacity between the plate and filament electrodes of said audion as another arm of said network, said input and output circuits being connected respectively as conjugate arms of said network, and means for supplying direct current to said plate electrode.

19. A multi-stage amplifying system including an input circuit, an output circuit and an audion in each stage, the grid-plate inherent capacity of each audion coupling

the input and output circuits of each stage, and a balanced network of pure capacities only, including said grid-plate coupling capacity as one arm of said network and a capacity between the plate and filament electrodes of said audion as another arm of said network, said input and output circuits of each stage being connected respectively as conjugate arms of said network. 70

20. A multi-stage amplifying system including an input circuit, an output circuit and an audion in each stage, the grid-plate inherent capacity of each audion serving to couple the input and output circuits of each stage, a balanced network of pure capacities only, including said grid-plate capacity as one arm of said network and a capacity between the plate and filament electrodes of said audion as another arm of said network, said input and output circuits of each stage being connected respectively as conjugate arms of said network, and means for supplying direct current to the said plate electrode of the audion in each stage. 75

21. A multi-stage amplifying system having in each stage an input circuit, a tuned output circuit, an audion capacitively coupling said circuits, a balanced network of pure capacities only, including the coupling capacity as one arm of said network and a capacity between the plate and filament electrodes of said audion as another arm of said network, said input and output circuits being connected respectively as conjugate arms of said network. 80

22. An amplifying system having an input circuit, an output circuit, an audion capacitively coupling said circuits, the output circuit of said audion being linked to the input circuit of a succeeding audion by means including a tunable circuit, and a balanced network of pure capacities only, including the coupling capacity as one arm of said network and a capacity between the plate and filament electrodes of said first mentioned audion as another arm of said network, said input and output circuits being connected respectively as conjugate arms of said network. 100

23. An audion amplifier stage having an input circuit, an output circuit, an audion capacitively coupling said circuits, the plate circuit of said audion being linked to the grid circuit of a succeeding audion by capacitive coupling means, and a balanced network of pure capacities only, including said coupling capacity as one arm of said network and a capacity between the plate and filament of said first-mentioned audion as another arm of said network, said input and output circuits being connected respectively as conjugate arms of said network. 110

24. An electric system including an input circuit, an output circuit, an audion having grid-plate capacity coupling said circuits. 120

and a balanced network of pure capacities only, including said grid-plate capacity as one arm of said network and a substantially larger capacity between the plate and filament electrodes of said audion as another arm of said network, said input and output circuits being connected respectively as conjugate arms of said network.

25. An electric system including an input circuit, an output circuit, an audion having grid-plate capacity coupling said circuits, and a balanced network of pure capacities only, including said grid-plate capacity as one arm of said network, and an added capacity between the plate and filament electrodes of said audion, said added capacity being substantially larger than the inherent plate-filament capacity and forming therewith another arm of said network, said input and output circuits being connected respectively as conjugate arms of said network.

26. An electric system including an input circuit, an output circuit, an audion having grid-plate capacity coupling said circuits, and a balanced network of pure capacities only, including said grid-plate capacity as one arm of said network and a capacity between the plate and filament electrodes of said audion as another arm of said network, said input and output circuits being connected, respectively, as conjugate arms of said network, the ratios of the values of the capacities of said network being such that the alternating-current voltage introduced between said plate and filament electrodes is minimized.

27. An electric system including an input circuit, an output circuit, an audion having grid-plate capacity coupling said circuits, and a balanced network of pure capacities only, including said grid-plate capacity as one arm of said network and a capacity of the order of one hundred times larger than said grid-plate capacity between the plate and filament electrodes of said audion as another arm of said network, said input and output circuits being connected, respectively, as conjugate arms of said network.

28. An amplifier including an audion having an input circuit and an output circuit, one terminal of said output circuit being connected to the plate electrode of said audion, and thru a capacity to the filament circuit of said audion, the second terminal of said output circuit being connected thru a second capacity to the grid electrode of said audion, and thru a third capacity to said filament circuit, said first-named capacity being the largest and said second-named capacity being the smallest, whereby undesirable capacitive coupling between said grid and plate electrodes is neutralized and the amplification is maintained at a high degree.

29. An amplifier including an audion having an input circuit and an output circuit, one

terminal of said output circuit being connected to the plate electrode of said audion and thru a capacity to the filament circuit of said audion, the second terminal of said output circuit being connected thru a second capacity to the grid electrode of said audion, and thru a third capacity of a value substantially less than that of said first-named capacity to said filament circuit, whereby undesired capacitive coupling between grid and plate electrodes is neutralized and the amplification is maintained at a high degree.

30. In a radio-frequency amplifier, two audions, each of which has grid, plate and filament electrodes, the filament electrodes of said audions being connected together thru a filament system, and a coupling system interposed between said audions, said coupling system including a radio-frequency coil and four capacities effectively connected two from the terminals of said coil to the grid electrode of the first audion and two from the terminals of said coil to said filament system, one of said last-named two capacities being substantially larger than the other whereby a step-up voltage ratio is maintained in said coupling system.

31. A radio-frequency amplifier including two audions whose filaments are connected together thru a filament system, each audion having grid and plate electrodes, a coupling system interposed between said audions, said coupling system including a radio-frequency coil and essentially four capacities, one of the terminals of said coil being connected thru the first of said capacities to the grid electrode of the first of said audions and thru the second of said capacities to the filaments of said audions, the other terminal of said coil being connected thru the third of said capacities to the grid electrode of the first said audion, and thru the fourth of said capacities to the filaments of said audions, the input terminals of said coupling system being effectively the terminals of said second capacity and the output terminals of said coupling system being effectively the terminals of said fourth capacity, the value of said second capacity being substantially greater than the value of said fourth capacity, whereby a step-up ratio is maintained in said coupling system.

32. In an amplifier stage including an input circuit and an output circuit, an audion having grid, plate and filament electrodes and grid-plate capacity coupling said circuits, and an impedance bridge balanced substantially throughout a desired frequency range and of which said input and output circuits are conjugate arms, said bridge including as one impedance arm the grid-plate capacity of said audion, and as another arm an impedance between the plate and filament of said audion, the impedance of said grid-plate capacity being substantially greater than said impedance between plate and filament throughout

said desired frequency range, whereby the amplification of said stage is maintained at a high degree.

33. In an amplifier stage including an input circuit and an output circuit, an audion having grid, plate and filament electrodes and grid-plate capacity coupling said circuits, and an impedance bridge substantially balanced throughout a desired frequency range and of which said input and output circuits are conjugate arms, the balancing arms of said bridge comprising four impedances, of which one is said grid-plate coupling capacity and the remaining three including a capacitive arm and two arms comprising impedances having like character throughout said desired frequency range, one of said remaining three arms being connected between said plate and filament electrodes and having an impedance substantially smaller than that of said grid-plate coupling capacity, whereby the amplification of said stage is maintained at a high degree.

In testimony whereof I affix my signature.
HAROLD A. WHEELER.

Certificate of Correction

Patent No. 1,757,494.

Granted May 6, 1930, to

HAROLD A. WHEELER

It is hereby certified that error appears in the printed specification of the above numbered patent requiring correction as follows: Page 3, lines 78 and 79, for the ratio $\frac{C_1}{C_2}$ read $\frac{C_2}{C_1}$; page 6, line 64, claim 19, for the misspelled compound word "gride-plate" read *grid-plate*; and that the said Letters Patent should be read with these corrections therein that the same may conform to the record of the case in the Patent Office.

Signed and sealed this 27th day of May, A. D. 1930.

[SEAL.]

M. J. MOORE,
Acting Commissioner of Patents.
